UNITED STATES PATENT OFFICE

2,032,223

OIL OR GASOLINE BARREL LOCK

Albert Ostgaard, Cadogan, Alberta, Canada, assignor of one-half to Walter Ganser, Provost, Alberta, Canada

Application December 21, 1934, Serial No. 758,641
In Canada December 20, 1934

5 Claims. (Cl. 70—125)

My invention relates to improvements in barrel locks, more particularly locks for securing the closures for filler and outlet openings in the barrel.

5 In barrels of a character having filler and outlet openings, the one normally closed by a screw plug and the other by a faucet, a locking attachment has been provided by means of which a lock can be applied securing both plug and faucet.

10 In the present arrangement an upper head is provided having a hinged gate enclosing the filler screw, said head including a locking staple, and a locking assembly having one end engaged with the faucet valve stem and the other end engageable with the staple.

15 The present invention is directed to providing an improved locking assembly forming the connection between the faucet valve stem and locking staple, one of the objects of the invention being to provide a simplified attachment of this character adapted to prevent removal of the faucet from the outlet opening and also locking the faucet valve stem against movement.

20 An important feature of the invention is the simplification of the parts by which adjustment of the device to accommodate variations in the spacings between the barrel openings is virtually automatic.

25 Other features of my invention will become apparent from the accompanying description taken in conjunction with the drawing wherein like characters of reference indicate like parts throughout the several views and wherein:

30 Fig. 1 is a side view partly in vertical section of the device in attachment to the plug and faucet of a barrel, a portion of the latter being shown in section.

35 Fig. 2 is a plan view of the device attached in locking relation to a barrel plug and faucet, a portion of the barrel being indicated.

40 Fig. 3 is a plan view of a portion of a barrel and showing particularly a plug and locking head, the latter being illustrated without the closure cap.

45 Figs. 4 and 5 are detail front and side views of a portion of the faucet including the external portion of the stem.

50 Figs. 6 and 7 are front and side views respectively of the outer member of the locking bar assembly.

55 Figs. 8 and 9 are front and side views respectively of the inner member of the locking bar assembly.

Having reference to the drawing 1 indicates a

portion of the end wall of a barrel provided with the usual spaced screw threaded filler and discharge openings 2 and 3, said openings in the present showing being closed, the one by a closure plug 4 and the other by a discharge faucet 5.

5 In conjunction with the closure plug there is provided a locking attachment substantially conforming to prior conceptions of a barrel lock. Said attachment includes a head 6 provided with a shank 7 carrying a staple 8. The head 6 is in the form of a flat plate formed with a circular opening 10 adapted to overlie the opening 2 of the barrel end. A cap 11 is hinged to the head 6 and is formed with an interior cavity which forms a space for the head of the plug 4. The cap 11 is formed with a slot 12 for reception of the staple 8.

10 As a locking arrangement for the faucet I provide a simplified structure that is virtually automatically adjustable, said structure forming the principal subject matter of the present invention. This comprises relatively endwise shiftable inner and outer members respectively indicated at 13 and 14, said members being adapted for concentric arrangement to provide a locking bar assembly.

15 The outer member 14 (see particularly Figures 6 and 7) is of cylindrical formation and has the upper end portion cut away or flattened to provide a flat strap 15 with slotted opening 16 for reception of the staple 8.

20 The inner member 13 is dimensioned to be concentrically received within the cylindrical portion of the outer member 14 and includes a bifurcated lug 17 adapted for attachment by a pin 18 to the stem 19 of the faucet 5, said stem 19 being suitably flattened for engagement by the lug 17.

25 To prevent relative rotation of the members 13 and 14 the inner member 13 is provided with a transverse pin 20 laterally projecting and slideable in elongated opposing slots 21 formed in the outer member 14. This facilitates use of the locking bar assembly as a lever or handle for turning the valve stem 19 when said assembly is disengaged from the staple 8.

30 It is obvious that the device provides a greatly simplified arrangement for securing both the faucet and valve stem therefor and also for cooperative locking engagement with the head and cap for the plug 2 through the use of a padlock 22 applied to the staple 8.

35 The members 13 and 14 being endwise relatively shiftable to the limits permitted by travel of the pin 20 in the slots 21, adjustment of the as-

sembly to accommodate variations in spacings of the faucet and plug openings becomes virtually automatic and occurs as a matter of course in attaching the outer member to the staple 8.

It is to be understood that while I have herein shown and described one specific embodiment of my invention changes in form construction, and method of application may be made within the scope of the appended claims.

10. What I claim is:

1. A locking bar assembly for barrel locking attachments, said assembly comprising inner and outer endwise relatively shiftable members, said members including cylindrical portions concentrically arranged, the inner member having one end adapted for pivotal engagement with the valve stem of a faucet and the outer member having a strap portion engageable with a locking staple, the outer member being formed with opposing longitudinal slotted openings, and the inner member having a laterally projecting guide pin arranged for travel in said openings.

2. A locking bar assembly for barrel locking devices comprising two endwise relatively shiftable co-operating members, the end portion of the one being directly attachable to the valve stem

of a faucet in a manner to prevent rotation thereof independently of the assembly, and the other directly engageable with a locking staple.

3. A device as defined in claim 2 wherein the cooperating portions of said members comprise cylindrical body portions concentrically assembled together.

4. A locking bar assembly for barrel locking devices comprising two concentrically arranged cylindrical members adapted for endwise relative shifting movement, the one being formed with a bifurcated end adapted for pivotal attachment to the valve stem of a faucet, and the other having a slotted strap portion engageable with a locking staple.

5. A locking bar assembly for barrel locking devices comprising two concentrically arranged cylindrical members adapted for endwise relative shifting movement, the one being adapted for pivotal attachment to the valve stem of a faucet and the other engageable with a locking staple, and a guide pin on the one member arranged for travel in longitudinal slotted openings formed in the other member.

25. ALBERT OSTGAARD.
